UNITED STATES PATENT OFFICE.

HARVEY P. JONES, OF CHICAGO, ILLINOIS.

HOLDER.

SPECIFICATION forming part of Letters Patent No. 707,234, dated August 19, 1902.

Application filed April 17, 1902. Serial No. 103,371. (No model.)

To all whom it may concern:

Be it known that I, HARVEY P. JONES, a citizen of the United States, residing at Chicago, in the county of Cook and State of Illinois, have invented a new and useful Improvement in Holders, of which the following is a specification.

My invention relates to holders and has particular reference to loose - leaf holders which employ containing cover - sections spring-actuated and pintled at one side and having a pintled sectional upper cover adapted to freely turn and fold back upon one of its sections, and my invention lies in the improved construction of the pindle and attendant parts of the holder.

My primary object is to simplify the pindle connections and facilitate the assembling of parts and the adjustment of spring-tension at the pindle and also to provide a simple stop to regulate the degree of separation of the cover-sections.

My invention is shown in its preferred embodiment in the accompanying drawings, in which—

Figure 1 is a perspective view of my improved holder; Fig. 2, a broken view in perspective showing the stop means employed; Fig. 3, a view in perspective showing the manner of inserting loose leaves into the holder; Fig. 4, a broken sectional view taken as indicated at line 4 of Fig. 5; Fig. 5, a view taken as indicated at line 5 of Fig. 4; Fig. 6, a sectional view taken as indicated at line 6 of Fig. 4, and Fig. 7 a perspective view showing the parts of the holder before they are assembled.

A represents one of the cover-sections of a holder having annular projections or pindle-carriers a , a' , a'' , and a''' . The annular projections a , a' are provided with shoulders or offsets a^3 . The annular projection a^3 is provided with perforations a^4 for receiving a pin or spring-retainer a^5 .

B represents the other cover-section, formed in two parts or sections B' and B'' . The parts B' and B'' are provided on adjacent edges with the annular projections B^3 , which form an annular opening to receive the pindle-bar B^4 .

The part B' is provided on its opposite edge with annular projections b , b' , b'' , b''' . The projections b , b' are provided with perforations

b^3 , which receive pins b^3 . The projections b are also provided with shoulders or offsets b^4 , which coact with the offset a^3 above mentioned.

C is a pindle composed of the cylindrical bars c , having longitudinal grooves c' and perforations c^4 , adapted to receive the pins b^3 and provided at their ends with slots c^3 to serve as a means for receiving a screw-driver or other suitable tool to turn the bars when the parts are assembled, and a reverse-wound coil-spring having the main reverse-wound coils c^4 , connected by a loop c^5 and having at their free ends lateral extensions c^6 , adapted to fit within the grooves c' of the cylindrical bars. The parts are assembled by bringing the annular projections into alinement with each other to thus form a continuous opening. The lateral extensions of the spring are inserted into the grooves in the pindle-sections c , and the assembled pindle is then put in place to connect the cover-sections. The spring is then secured at its central portion by the pin a^6 , which passes through the perforations a^4 and the loop c^5 . The pindle-sections c are then turned until the proper tension is produced in the coils and the perforations in the bar register with the perforations in the annular projections b , b' of the part B' . Said pindle-sections are then secured in this position by inserting the pins b^3 into the perforations. When the parts are thus assembled, the shoulders or offsets a^3 , a^3 , b^4 , b^4 are in a position where they oppose each other and serve to prevent the further separation of the cover-sections past a predetermined point.

The operation of the holder is well understood. The upper cover-section is raised against the tension of the spring by a well-understood prying action and the leaves inserted between the spring-actuated portions. The pressure of the cover-section serves to hold the loose leaves in position, at the same time permitting of the ready removal of the same. The upper cover-section being freely hinged, the free portion of the top cover-section may be folded back upon the spring-actuated portion, thus presenting the surfaces of the loose leaves.

Changes in minor details of construction within the spirit of my invention may be

made. Hence no undue limitation is to be understood from the foregoing detailed description.

What I regard as new, and desire to secure by Letters Patent, is—

- 5 1. In a holder, the combination of cover-sections, with a pintle comprising a spring connected with one of said covers, and pintle-sections attached to the ends of said spring and connected with the opposite cover.
- 10 2. In a holder, the combination of cover-sections, with a pintle comprising a spring with reverse-wound spiral coils attached at its central portion to one of said covers, pintle-sections attached to the ends of said spring and connected with the opposite cover.
- 15 3. In a holder, the combination of cover-sections, with a pintle comprising a spring with reverse-wound spiral coils provided at its central portion with a loop to secure said spring to one of said cover-sections and lateral straight extensions, and pintle-sections having longitudinal grooves, said grooves serving to receive said extensions, said pintle-sections being connected with the opposite cover.
- 20 4. In a holder, the combination of cover-sections having annular projections, said projections having thereon opposed shoulders or

offsets, and a pintle comprising a spring with 30 reverse-wound coils connected with one of said cover-sections and pintle-sections attached to said spring, said pintle-sections being connected with the other one of said cover-sections.

35 5. In a holder, the combination of cover-sections, with a pintle composed of a spring with reverse-wound coils attached at its central portion to one of said covers and pintle-sections attached to said spring extending 40 approximately to the edge of said covers, means for turning the pintle-sections and means for securing the pintle-sections to the opposite cover when the spring is adjusted.

6. In a holder, the combination of cover-sections provided with pintle-receiving perforations, with a pintle composed of a torsion-spring connected with one of said sections at the pintle, a pintle-section connected with said spring and serving to produce torsion in 50 the spring, and means for securing said pintle-section while under stress to the other cover-section, substantially as described.

HARVEY P. JONES.

In presence of—

W. GIFFORD JONES,
E. R. JONES.
